[57] CLAIM

The ornamental design for a diagnostic image display console for use with digital radiography, computerized tomography or nuclear magnetic resonance imaging, as shown and described.

DESCRIPTION

FIG. 1 is a front perspective view of a diagnostic image display console for use with digital radiography, computerized tomography or nuclear magnetic resonance imaging showing our new design.

FIG. 2 is a front elevational view thereof.

FIG. 3 is a side elevational view thereof.

FIG. 4 is a front perspective view thereof, with table top portion removed;

FIG. 5 is a front elevational view thereof; and

FIG. 6 is a side elevational view thereof.

The rear of the console is substantially plain and unornamented.
